UNITED STATES PATENT OFFICE.

EDWARD T. ADAMS, OF LOS ANGELES, CALIFORNIA, ASSIGNOR TO JOSEPH G. RICHARDSON, OF LOS ANGELES, CALIFORNIA.

SAND-EJECTING MEANS FOR DEEP-WELL PUMPS.

Application filed August 27, 1924. Serial No. 734,405.

To all whom it may concern:

Be it known that I, EDWARD T. ADAMS, a citizen of the United States, and a resident of Los Angeles, in the county of Los Angeles and State of California, have invented new and useful Improvements in Sand-Ejecting Means for Deep-Well Pumps, of which the following is a specification.

The present invention relates to deep well pumps, and pertains more particularly to means for ejecting sand from the pump.

The principal object of the invention is to provide a deep well pump which will not tend to become sanded. It will be understood, in the consideration of this invention, that in hollow plunger and bucket valve types of pumps there is provided a stationary pump barrel and a working barrel or plunger reciprocal in same. The lower end 20 of the pump barrel is provided with a ball check, generally referred to as the standing valve, and operating as a suction valve. The plunger, which is tubular and a working fit in the barrel, is provided with an upwardly opening valve known as the discharge valve.

When pumps of this type are in operation, the upstroke of the plunger accomplishes displacement of oil then existing above the working valve, and incidentally oil is drawn upward through the standing valve during the same stroke. During this upstroke, the maximum discharge pressure exists above the plunger, and a reduced pressure exists 35 below. It is because of this pressure difference that the usual slip or leak occurs, oil flowing downward through the working clearance between the barrel and plunger into the space immediately above the standing valve. This oil, of course, always carries a certain percentage of silt, or sand, as it is generally referred to. Such sand having found its way into that space immediately above the standing valve tends to become 40 lodged there, and eventually interferes with the action of the valve, and at times even prevents the plunger from reaching the end of its down stroke.

It is this condition which it is the object 50 of this invention to eliminate. A pump having become sanded up can be again put into operation only by removing it from the well and cleaning it or by more or less problematical washing methods. Since leakages 55 must occur because of the necessary work-

ing clearances between the plunger and the pump barrel, and since oil from deep wells always contains more or less sand, I have set out to provide a simple construction of pumps whereby the sand may be caused to 60 separate largely from the oil which leaks by the plunger.

Another and important object of this invention is to provide means whereby sand so separated from the oil will be subsequently 65 ejected to points where it will not again tend to settle about the standing valve.

Another object of this invention is to reduce the usual loss or slip while permitting of using a reasonable clearance between the working parts. It will be apparent that by providing ample clearance, together with means for reducing the slip, there will be created a pump which will be 70 equally as efficient after considerable use as 75 when originally installed.

Another object of this invention is to provide a pump of the above mentioned character in which the tendency of extremely fine silt to reach the standing valve by 80 leakage is greatly reduced.

Still another object is to provide for carrying out the objects mentioned without reducing the effective plunger area.

Still other objects and advantages of my 85 invention will appear hereinafter and will be better understood by virtue of the order of their occurrence.

I have illustrated by the accompanying drawings one practical embodiment of my 90 invention.

In the said drawings,

Figure 1 is a view in vertical section of the said embodiment;

Figure 2 is a view in section seen on a 95 line 2—2 of Figure 1;

Figure 3 is a view in section seen on a line 3—3 of Figure 1; and

Figure 4 is a view in section seen on a 100 line 4—4 of Figure 1.

The embodiment illustrated in some respects very closely resembles the old-fashioned single acting oil well pump in that there is provided a tubular pump barrel 5 and a tubular working barrel or plunger 6, the latter being a normal running fit within the pump barrel.

To the upper end of the plunger there is attached a working valve cage 7 providing an annular valve seat 8 on which the work- 110

ing valve ball 9 rests. The cage is provided with the usual externally threaded boss 10 by means of which the plunger is connected to the usual sucker rods (not shown). The 5 pump barrel is externally threaded at its upper end as at 12 to receive a tubing collar 13 by means of which the pump barrel may be attached to the usual string of tubing (not shown) which extends upward through 10 the well to carry out fluid raised by the pump.

The interior space of the pump barrel is designated in the drawings by the letter B and this space is subject at all times to the 15 full hydrostatic pressure of the fluid column reaching to the surface. The interior space of the tubular plunger is designated by the letter C, and being below the suction valve is subject during the down stroke of the 20 pump to the maximum pressure just mentioned, while during the upstroke it is subject only to pressure equal to the normal oil level in the well. The bore A of the well and the space A immediately below the 25 standing ball valve 15 are subject to the last mentioned pressure only.

Ball 15 rests upon an annular seat 18 which is carried at the lower end of the pump barrel, and, as in usual pumps, this 30 ball when seated effectively closes the lower end of the pump against any downward flow of fluid from the space C. It will be apparent from the foregoing that reciprocation of the plunger within the barrel will 35 produce the pumping action common to single acting hollow plunger oil well pumps.

A salient feature of this invention resides in the provision of an annular coaxial wall 16 forming a part of the pump barrel and 40 extending from the lower end of the barrel upwardly into the bore C of the tubular plunger. This wall encompasses a central fluid course C' which is always in direct communication with the space C. The arrangement of the annular wall provides an 45 annular space E in which the plunger is a running fit, the lower portion of the space E being always unoccupied by the annular plunger. Space E is hereinafter referred to 50 as the "sand trap."

The construction shown for the pump barrel provides the lower annular portion 18 of appreciable thickness, and through this there are drilled a plurality of holes 19 penetrating the lower end of portion 17 and providing an outlet from the space E. These 55 drilled holes, or sand outlets, are counterbored or enlarged, as at 20, to provide valve seats 21 and to house a spring 22 and a bushing 23. A ball 24 is provided in each counterbore and is held upon its seat by the tension of the spring.

The parts just mentioned provide in effect 60 a plurality of downwardly opening check valves which permit of oil and sand being

ejected downwardly from space E while being checked from returning to space E.

In assembling a bushing ball and spring, the spring should be compressed a predetermined degree in order that the ball will not 70 be moved from its seat until the pressure difference between the fluid above and below it is at least equal to the pressure difference between the pressure in B and the pressure in A. The reason for this is apparent 75 from the following:

Considering the pump as a whole and assuming that the working valve is tight, it will be seen that by virtue of the construction shown and described, fluid cannot slip or leak from B to C except by passing downward through a long reduced clearance space to space E and thence upward again through an equally long reduced clearance space to the space C. During the up stroke of the pump, as well as during the down stroke of the pump, the pressure in B will always be considerably above that in A and A', and, therefore, if the ball check is not subject to any considerable spring tension, oil, having 80 reached E from B, would escape into space A'. In such case, the intention of the inner annular wall as a means for increasing resistance to leakage would be defeated. Therefore, by setting the sand outlet valves 85 under the compression mentioned, fluid will not tend to leak from B to E to A'.

In order to fully explain the operation of this pump, the operation in a general way will be explained first, and subsequently the 90 operation of the pump and the sand ejecting means under three specific practical conditions will be considered. The first one of the practical conditions to be considered is that in which during the up stroke of the 105 plunger the effective volume of space E increases at a rate more rapid than it will fill with oil by leakage. The second practical condition to be considered will be that in which it is assumed that the leakage from B to E is just sufficient to keep the space E filled as it increases in volume. The third practical condition to be considered is that condition under which the clearance is either unduly large or has become worn so that 110 fluid will leak from B to E more rapidly than the volume of E increases, with the result that during the up stroke of the pump the pressure in E will be substantially a compromise between the pressure in B and the pressure in C.

Considering the pump generally, in its 115 operation, it will be seen that during the down stroke the pressure in B and C will be the maximum discharge pressure, the pressure in A and A' remaining substantially constant at all times whether the pump is operating or not. In so far as leakage is concerned, the difference between the pressure in B and A need not be considered, because 120

- of the fact that the check valves are set under sufficient compression to resist flow from E to A', even were the pressure in E as high as it is at any time in B. Therefore, it will be seen that during the down stroke of the pump there is no tendency for leakage through the clearances between the relatively reciprocating parts. During the up stroke of the pump, some fluid will find its way into space E. This fluid will contain silt or sand, provided it is peculiar to the well, and while the sand may be readily washed down from B to E, it is quite apt to settle in E rather than to again be carried through the clearance from E to C. Regardless of the amount of fluid and sand which may find its way into E during the up stroke, it will be apparent that during the next down stroke of the plunger the space E will be so decreased in volume that the sand and oil occupying space E will be displaced. It is true that a slight pressure in excess of the pressure of the oil in B will be required to open the check valves and eject the sand, but obviously the weight and inertia of the reciprocating parts is sufficient to accomplish this. In fact, the slight amount of energy required at the end of the down stroke of the plunger to eject the sand and leakage will act as an excellent cushion for said reciprocating parts.
- Now that the general operation of the pump has been described, it will be assumed that the pump is operating under the first mentioned of the above conditions. Under this condition, E will not be completely filled with oil at the end of the up stroke and, therefore, the pressure of the contents of E will be negligible and there might even be a tendency during the up stroke for fluid to be drawn from C into E, but there would be no objection to this and only a slight loss of energy. Now, since the pressure in E during the up stroke under the condition being assumed cannot be greater than C, certainly there can be no leakage. In this case, it may be said of this pump that while a certain amount of slippage may occur, that slippage does not reach the space between the working valve and the standing valve and, therefore, cannot carry sand or silt into the space C or to the standing valve, and any sand or oil which may get so far as E will be ejected downward from the pump into the well where it can do no harm.
- Under the second of the above mentioned conditions, space E will fill as rapidly as it is increased during the upstroke of the plunger, but the effect will be no different than in the first instance.
- Now, as to the third operating condition: The up stroke of the plunger will find space E filling as rapidly as it is formed, and the pressure of the fluid in space E constantly increasing until it attains a pressure about midway between the pressure then existing in B and the pressure then existing in C. The result is that fluid will tend to flow from E upward through the reduced clearance to C. This is the most unfavorable operating condition to which this pump can be subject, but, of course, slippage is common to all pumps and it may be said in favor of this pump that even under unfavorable operating conditions the length of the reduced clearance through which the oil has to travel before it can get from space B to space C is at least twice as great as it is in other types of single acting pumps.
- The fact remains, however, that even with such leakage in the third instance there will always be the same tendency for sand to be ejected through the check valves before it can reach spaces C and C'.
- It will be apparent now that by the addition of an inner annular wall and a plurality of check valves to an otherwise common type of pump, I have provided for carrying out the above objects. While I have shown and described a specific arrangement of valves and annular walls for carrying out my invention, I do not limit myself to any specific arrangement, except as determined by the appended claims.
- I claim as my invention:
1. In a pump, a double-concentric-walled member providing an annular intermediate space and an inner fluid course, a single walled member reciprocal relative to the double walled member, in said space, valves coacting with the aforementioned members so that relative reciprocation produces flow through said fluid course, and a port leading from the annular space downwardly to points below and externally of the pump.
  2. In a pump, a double-concentric-walled member providing an annular intermediate space and an inner fluid course, a single walled member reciprocal relative to the double walled member in said space, valves coacting with the aforementioned members so that relative reciprocation produces flow through said fluid course, and a port leading from the lowermost part of the unoccupied portion of said annular space to points externally of the annular space.
  3. In a pump, a double-concentric-walled member providing an annular intermediate space and an inner fluid course, a single walled member reciprocal relative to the double walled member in said space, valves coacting with the aforementioned members so that relative reciprocation produces flow through said fluid course, and a port leading from the lowermost unoccupied portion of the annular space to points below and externally of the pump.
  4. In a pump, a double-concentric-walled member providing an annular intermediate

- space and an inner fluid course, a single walled member reciprocal relative to the double walled member in said space, valves coacting with the aforementioned members 5 so that relative reciprocation produces flow through said fluid course, and a port leading from the lowermost unoccupied portion of the annular space to points below the lowermost of the valves.
- 10 5. In a pump, a double-concentric-walled member providing an annular intermediate space and an inner fluid course, a single walled member reciprocal relative to the double walled member in said space, valves 15 coacting with the aforementioned members so that relative reciprocation produces flow through said fluid course, and a port leading from the annular space downwardly to points below and externally of the pump, 20 and non-return valvular means controlling said port.
6. In a pump, a double-concentric-walled member providing an annular intermediate space and an inner fluid course, a single 25 walled member reciprocal relative to the double walled member in said space, valves coacting with the aforementioned members so that relative reciprocation produces flow through said fluid course, a port leading 30 from the lowermost part of the unoccupied portion of said annular space to points externally of the annular space, and non-return valvular means controlling said port.
7. In a pump, a double-concentric-walled 35 member providing an annular intermediate space and an inner fluid course, a single walled member reciprocal relative to the double walled member in said space, valves coacting with the aforementioned members 40 so that relative reciprocation produces flow through said fluid course, a port leading from the lowermost unoccupied portion of the annular space to points below and externally of the pump, and non-return valvular 45 means controlling said port.
8. In a pump, a double-concentric-walled member providing an annular intermediate space and an inner fluid course, a single walled member reciprocal relative to the 50 double walled member in said space, valves coacting with the aforementioned members so that relative reciprocation produces flow through said fluid course, a port leading from the lowermost unoccupied portion of the annular space to points below the lowermost of the valves, and non-return valvular 55 means controlling said port.
9. In a pump, a pump cylinder, a tubular plunger reciprocal from the lower portion of the annular space between the cylinder and tube downwardly and through 60 said closure to points below and externally of the pump and the suction valve.
10. In a pump, a cylinder, a smaller concentric inner tube, means connecting the tube and cylinder adjacent the lower end to provide an annular space open at the upper end and substantially closed at the lower end, an annular plunger member reciprocal 70 in said annular space, and means whereby sand and the like settling in the lowermost unoccupied portion of the annular space will be ejected therefrom by reciprocation of plunger.
11. In a pump, a pump cylinder, a tubular plunger reciprocal in said cylinder, a bottom closure wall to said cylinder, a standing tube rising from said closure and extending into said plunger, a suction valve 75 through which oil is drawn into the bore of the standing tube by upward movement of said plunger, a port leading from the lower portion of the annular space between the cylinder and tube, downwardly through said closure to points below and externally of the pump and the suction valve, and downwardly opening non-return means controlling said port.
12. In a pump, a pump cylinder, a tubular plunger reciprocal in said cylinder, a bottom closure wall to said cylinder, a standing tube rising from said closure and extending into said plunger, a suction valve 80 through which oil is drawn into the bore of the standing tube by upward movement of said plunger, a port leading from the lower portion of the annular space between the cylinder and tube, downwardly through said closure to points below and externally of the pump and the suction valve, and downwardly opening non-return means controlling said port.
13. In a pump, a pump cylinder, a tubular plunger reciprocal in said cylinder, a bottom closure wall to said cylinder, a standing tube rising from said closure and extending into said plunger, a suction valve 85 through which oil is drawn into the bore of the standing tube by upward movement of said plunger, a port leading from the lower portion of the annular space between the cylinder and tube, downwardly through said closure to points below and externally of the pump and the suction valve, and downwardly opening non-return means controlling said port.
14. In a pump, a pump cylinder, a tubular plunger reciprocal in said cylinder, a bottom closure wall to said cylinder, a standing tube rising from said closure and extending into said plunger, a suction valve 90 through which oil is drawn into the bore of the standing tube by upward movement of said plunger, a port leading from the lower portion of the annular space between the cylinder and tube, downwardly through said closure to points below and externally of the pump and the suction valve, and downwardly opening non-return means controlling said port.
15. In a pump, a pump cylinder, a tubular plunger reciprocal in said cylinder, a bottom closure wall to said cylinder, a standing tube rising from said closure and extending into said plunger, a suction valve 95 through which oil is drawn into the bore of the standing tube by upward movement of said plunger, a port leading from the lower portion of the annular space between the cylinder and tube, downwardly through said closure to points below and externally of the pump and the suction valve, and downwardly opening non-return means controlling said port.
16. In a pump, a pump cylinder, a tubular plunger reciprocal in said cylinder, a bottom closure wall to said cylinder, a standing tube rising from said closure and extending into said plunger, a suction valve 100 through which oil is drawn into the bore of the standing tube by upward movement of said plunger, a port leading from the lower portion of the annular space between the cylinder and tube, downwardly through said closure to points below and externally of the pump and the suction valve, and downwardly opening non-return means controlling said port.
17. In a pump, a pump cylinder, a tubular plunger reciprocal in said cylinder, a bottom closure wall to said cylinder, a standing tube rising from said closure and extending into said plunger, a suction valve 105 through which oil is drawn into the bore of the standing tube by upward movement of said plunger, a port leading from the lower portion of the annular space between the cylinder and tube, downwardly through said closure to points below and externally of the pump and the suction valve, and downwardly opening non-return means controlling said port.
18. In a pump, a pump cylinder, a tubular plunger reciprocal in said cylinder, a bottom closure wall to said cylinder, a standing tube rising from said closure and extending into said plunger, a suction valve 110 through which oil is drawn into the bore of the standing tube by upward movement of said plunger, a port leading from the lower portion of the annular space between the cylinder and tube, downwardly and through said closure to points below and externally of the pump and the suction valve, and a spring pressed valve controlling said port arranged to prevent return of fluid through said port; said valve being adjusted to resist being opened by any normal pressure which exists in the said annular space during upward movement of the plunger.

EDWARD T. ADAMS.
